UNITED STATES PATENT OFFICE.

JOHN W. DARLEY, JR., OF BALTIMORE, MARYLAND, ASSIGNOR OF ONE-HALF TO DAVID E. EVANS, PHILIP HAMBURGER, LEON HAMBURGER, AND MICHAEL HOLZMAN, OF BALTIMORE, MARYLAND.

SHEET LIFTING AND COUNTING DEVICE.

SPECIFICATION forming part of Letters Patent No. 752,616, dated February 16, 1904.

Application filed October 29, 1903. Serial No. 179,085. (No model.)

To all whom it may concern:

Be it known that I, JOHN W. DARLEY, Jr., a citizen of the United States, residing at Baltimore, State of Maryland, have invented certain new and useful Improvements in Sheet Lifting and Counting Devices; and I do hereby declare the following to be a full, clear, and exact description of the invention, such as will enable others skilled in the art to which it appertains to make and use the same.

My present invention relates to improvements in sheet lifting and counting machines; and it is intended to provide a machine which will lift the corners of the sheets of paper *separately* and will register each corner so lifted. After the corner is lifted the sheets may be removed in any convenient way, as by the well-known air-blast apparatus.

In that class of machines which are adapted to lift a single sheet of paper from a pile it has heretofore been necessary to manually adjust the tension or pressure of the rubber lifting-finger on the paper, this adjustment being necessary on account of the varying thickness and quality of the paper and also on account of the difference in the same paper when printed or not. With the present invention the rubber lifting-finger has only a very slight initial pressure when it first touches the paper, just enough to insure contact of the rubber and paper, and the power that moves the lifting-finger and so buckles the paper is transmitted to the lifting-finger in such a way that an additional pressure of the finger is produced on the paper, which additional pressure increases as the resistance to the motion of the finger increases. Thus the finger starts to move and the pressure increases until the top sheet of paper slips on the second sheet. I find that the coefficient of friction of the rubber on the paper is about five times the coefficient of friction of paper on paper. Thus if the pressure is never more than enough to cause the top sheet of paper to move it follows that sufficient power cannot be transmitted to the second sheet to cause it to move. The parts also are so arranged that the force applied to the lifting-finger is resolved into the

pressure factor and the turning factor in a single piece, and thus great delicacy and permanency is obtained.

My invention will be understood by reference to the accompanying drawings, in which the same parts are indicated by the same letters throughout the several views.

Figure 1 is a perspective view of a table fitted with my improved apparatus. Fig. 2 shows a section through the casing inclosing the gearing for driving the rod of the lifting device, the other parts being shown in elevation. Fig. 3 shows the top of the casing for the gearing removed and the sleeve mounted on the rod in section. Fig. 4 shows a section along the line 4-4 of Fig. 2 looking down, and Fig. 5 shows the lifting-finger with some of the sheets of paper lifted above the same.

Referring now to Fig. 1, A represents any suitable platform mounted on any suitable support A'. This platform is provided with two fixed strips A' A² projecting above the same, which strips are placed at right angles to each other, but with the angle cut away to allow the corners of the strips of paper to project into the open corner. A³ represents an adjustable clamp-strip which may be adjusted toward the strip A², as by means of the slotted arm a and the clamp-screw a'. Thus the sheets of paper B are held neatly piled one above the other by means of the three strips A', A², and A³. The corners of these strips beneath the lifting-finger (shown at b in Fig. 5) rest upon a rounded piece a⁰, so as to give these corners a slight inclination and enable the lifting-finger to operate more effectively, as will be hereinafter described. Just in rear of the rounded piece a⁰ I provide an arm C, journaled in brackets C' and pressed down on the paper by a weak coil-spring C'. (Shown in Figs. 1 and 5.) D represents a treadle pivoted, as at d, and normally pressed upward by the spring D'. To this treadle a rod E for operating the counters F is connected, and these counters are so arranged as to register every downward movement of the treadle. To this treadle D and on opposite sides of the pivot d are connected the ends of the cord H,

which cord passes over idlers I I' in the bracket I^2 and then is wound on the drum K , which is loose on the shaft M , which shaft is journaled in the bearing N , rigidly attached to the platform A . This shaft has secured thereon the ratchet-wheel M' and the spiral gear M^2 . The ratchet-wheel M' engages the spring-pawl k , which is carried by the drum K and L , which is pivoted beneath the platform A , and thus this ratchet-wheel is held against backlash. The upper end of the shaft M carries the spiral gear M^2 , meshing in the spiral pinion P^2 , fast on the rod P , which carries the lifting-finger P^3 , faced with rubber or other material having a greater coefficient of friction with the paper or other material to be lifted than the sheets of material have with each other. The spiral gear is mounted in a suitable casing T , which is open, as at t , to permit the engagement of the spiral pinion P^2 therewith, and made integral with this casting is the casing T' for the end of the rod P , carrying the spiral pinion P^2 . The rear end of this rod P slides in a vertical slot t^0 in the casing T' , and the said rod carries a fixed sleeve P' , which has a bearing, as at p' , on the casing T' of such a shape as to permit of the rod P rocking thereon as a fulcrum. Thus it will be seen that the rod P rocks upward about this pivot p' through an angle which is limited by the length of the slot t^0 . In order to keep the rod normally tilted upward, or, in other words, with the lifting-finger normally bearing down on the sheets of paper, I provide the loose sleeve Q , mounted on the rod P and provided with an annular collar q , in which engages the spring R . (See Fig. 2.) This spring normally presses upward on the said collar q and may be adjusted by means of the nut r , as shown in Fig. 2. Thus it will be seen that the spring R causes the heel of the rod to tilt up and the lifting-finger P^3 to bear down on the corners of the paper. Moreover, the threads of the spiral gearing are so pitched as to supplement this action of the spring R .

The operation of the device is as follows: Referring to Fig. 3, when M^2 is turned in the direction of the arrow, the teeth of M^2 and P^2 being cut at an angle of forty-five degrees, the sleeve Q will be forced in the direction of the arrow 2 against the shoulder T' . The sole effect of this is a slight increase of friction. Also the pinion P^2 at the point of contact of its tooth with the tooth of M^2 will receive a pressure in a direction at right angles to the plane of motion of M^2 and toward the observer, looking at Fig. 3. This pressure will tend to revolve P^3 in the direction of the arrow 3, and since the rod P is fulcrumed at p' will cause the rubber p^3 to bear harder on the paper B . It will also be evident that the greater the pressure of the tooth of M^2 against the tooth of P^2 the greater will be the pressure of p^3 on the paper B , and as the pressure between the teeth is dependent upon the resistance to motion of

p^3 it follows that the pressure of p^3 on the paper B is dependent upon the resistance of the paper to movement. Suppose the parts to be in the initial position, (indicated by Fig. 1,) pressing down on the treadle D will cause the counters to register and will also cause the cord H to rotate the drum K in the direction indicated by the arrow in Fig. 4. This would cause the pawl k to drag around the ratchet-wheel M' , which would rotate the shaft M and with it the worm-wheel M^2 . As this worm-wheel revolves it will rotate the worm P^2 , causing the rod P to partially rotate until the adhesive surface p^3 of the lifting-finger engages the paper. If the sheet slips readily over the sheet below, the lifting-finger will continue to revolve through a further angle until it pushes up and passes under the corner of the paper, when the motion will be interrupted, due to the fact that the treadle has reached its lower limit of travel. Now if the treadle be released the spring D' will restore the parts to the initial position. If, however, the sheet to be lifted does not yield readily, the adhesive face p^3 will bite against the face of the sheet with increased force, due to the coaction of the spring R and of the worm-wheel M^2 and worm P^2 , and this increased pressure will continue until the top sheet slips on the sheet below, for since the coefficient of friction of the adhesive tip on the top sheet is greater than that between any two of the sheets it necessarily follows that the top sheet will slip on the sheet below before the adhesive tip slips on the top sheet. Thus it will be seen that the machine automatically adjusts itself for varying coefficients of friction between two of the sheets and for the varying resistance due to difference in thickness of the sheets, and thus the machine is adapted for use either with the thinnest paper, such as tissue-paper, or with heavier sheets, such as cardboard, and automatically adjusts itself to variations between these limits of thickness and resistance. Moreover, the spring R will cause the lifting-finger to press down on the top sheet whether the pile of sheets be high or low, while the wedging action of the worm-threads will cause the requisite pressure to be applied to the lifting-finger to push back and lift the corner of the top sheet. This action will be assisted by the curvature of the corners b^0 of the sheets, due to the rounded block a^0 . It will be evident that where the machine is to do heavy work the spring R may be set up under greater initial tension than where light work is to be done.

It will be obvious that various modifications might be made in the hereinbefore-described apparatus which could be used without departing from the spirit of my invention. Thus any other suitable platform may be provided, any other suitable way for rotating the shaft M intermittently may be adopted, and various other modifications in the construction and ar-

rangeiment of parts might be had without departing from the spirit of the invention.

Having thus described my invention, what I claim, and desire to secure by Letters Patent of the United States, is—

1. In a sheet-lifter, the combination with a moving adhesive finger, of means for producing a substantially uniform pressure of said finger on the sheets, and means for superposing a pressure on said finger which pressure increases as the resistance to motion of said finger increases, substantially as described.

2. In a sheet-lifter, the combination with a rotary adhesive finger acting under initial pressure on the sheet, and means for superposing a pressure on said finger which pressure increases as the resistance to motion of said finger increases, substantially as described.

3. In a sheet-lifter, the combination with a rolling rod provided with an adhesive finger adapted to engage the leaf, of a spring normally pressing said finger on said leaf, and means for superposing a pressure on said finger which pressure increases as the resistance to rotation of said finger increases, substantially as described.

4. The combination with a fulcrumed rod adapted to swing vertically about its fulcrum, of an adhesive finger carried by said rod, a spring normally pressing said finger, down on the paper, and means for rotating said rod, substantially as described.

5. The combination with a fulcrumed rod adapted to swing vertically about its fulcrum, of an adhesive finger carried by said rod, a spring normally pressing said finger down on the paper, and spiral gearing for rotating said rod, substantially as described.

6. The combination with a fulcrumed rod adapted to swing vertically about its fulcrum, of an adhesive finger carried by said rod, a spring normally pressing said finger down on the paper, and spiral gearing adapted to rotate said rod and at the same time to press said fingers more firmly on the paper when the adhesive finger encounters resistance in rotation, substantially as described.

7. In a sheet-lifter, the combination with a casing, of a rod fulcrumed in said casing and carrying at one end an adhesive finger, a sleeve loosely mounted on said rod, a spring engaging said sleeve, and pressing said finger down on the paper, means for holding said rod against lateral vibration, a spiral pinion on said rod, a spiral gear engaging said pinion, and adapted to press said finger down on said paper in conjunction with said spring when said finger encounters resistance to rotation, and means for rotating said pinion, substantially as described.

8. In a sheet-lifter, the combination with a casing, of a rod fulcrumed in said casing and carrying at one end an adhesive finger, a sleeve loosely mounted on said rod, and provided with an annular collar, a spring engaging said

annular collar, and pressing said finger down on the paper, means for holding said rod against lateral vibration, a spiral pinion on said rod, a spiral gear engaging said worm and adapted to press said finger down on said paper in conjunction with said spring when said finger encounters resistance to rotation, and means for rotating said worm-wheel, substantially as described.

9. The combination with a fulcrumed rod adapted to swing vertically about its fulcrum, of an adhesive finger carried by said rod, a spring normally pressing said finger down on the paper, and spiral gearing for rotating said rod, having its teeth so disposed as to press said finger down on the paper in conjunction with said spring with increasing pressure as the said finger encounters resistance to rotation, substantially as described.

10. The combination with a fulcrumed rod adapted to swing vertically about its fulcrum, of an adhesive finger carried by said rod, a spring normally pressing said finger down on the paper, means for adjusting the tension of said spring, and spiral gearing for rotating said rod, having its threads so disposed as to press said finger down on the paper in conjunction with said spring with increasing pressure as the said finger encounters resistance to rotation, substantially as described.

11. The combination with a fulcrumed rod adapted to swing vertically about its fulcrum, of an adhesive finger carried by said rod, a spring normally pressing said finger down on the paper, means for adjusting the tension of said spring, and spiral gearing adapted to rotate said rod and having the engaging teeth so disposed as at the same time to press said finger more firmly on the paper when the adhesive finger encounters resistance in rotation, substantially as described.

12. In a sheet-lifter, the combination with a casing, of a rod fulcrumed in said casing and carrying at one end an adhesive finger, a sleeve loosely mounted on said rod, a spring engaging said sleeve, and pressing said finger down on the paper, means for holding said rod against lateral vibration, a spiral pinion on said rod, a spiral gear engaging said worm, said pinion and gear having their threads so disposed as to press said finger down on said paper in conjunction with said spring when said finger encounters resistance to rotation, and means for rotating said spiral gear intermittently in the same direction, substantially as described.

13. In a sheet-lifter, the combination with a casing, of a rod fulcrumed in said casing and carrying one end of an adhesive finger, a sleeve loosely mounted on said rod, and provided with an annular collar, a spring engaging said annular collar, and pressing said finger down on the paper, means for holding said rod against lateral vibration, a spiral pinion on said rod, a spiral gear engaging said worm,

said pinion and gear having their threads so disposed as to press said finger down on said paper in conjunction with said spring when said finger encounters resistance to rotation, 5 and means for rotating said worm-wheel intermittently in the same direction, substantially as described.

14. The combination with a fulcrumed rod adapted to swing vertically about its fulcrum, 10 of an adhesive finger carried by said rod, a spring normally pressing said finger down on the paper, and spiral gearing adapted to rotate said rod and at the same time to press said finger more firmly on the paper when the 15 adhesive finger encounters resistance in rotation, a counter, and mechanism for driving said spiral gearing, and for simultaneously operating said counter, substantially as described.

20 15. In a sheet-lifter, the combination with a casing, of a rod fulcrumed in said casing and carrying at one end an adhesive finger, a sleeve loosely mounted on said rod, a spring engaging said sleeve, and pressing said finger down 25 on the paper, means for holding said rod against lateral vibration, a spiral pinion on said rod, a spiral gear engaging said pinion, and adapted to press said finger down on said paper in conjunction with said spring when 30 said finger encounters resistance to rotation, a counter, and means for simultaneously rotating said worm-wheel, and operating said counter, substantially as described.

16. In a sheet-lifter, the combination with 35 a casing, of a rod fulcrumed in said casing and carrying at one end an adhesive finger, a sleeve loosely mounted on said rod, and provided with an annular collar, a spring engaging said annular collar, and pressing said finger down 40 on the paper, means for holding said rod against lateral vibration, a spiral pinion on said rod, a spiral gear engaging said worm and adapted to press said finger down on said paper in conjunction with said spring when said finger encounters 45 resistance to rotation, a counter, and means for rotating said worm-wheel, and for simultaneously operating said counter, substantially as described.

17. The combination with a fulcrumed rod 50 adapted to swing vertically about its fulcrum, of an adhesive finger carried by said rod, and spiral gearing for rotating said rod, having its teeth so disposed as to press said finger down on the paper with increasing pressure 55 as the said finger encounters resistance to rotation, and means for rotating said worm-wheel intermittently in the same direction, substantially as described.

18. The combination with a fulcrumed rod 60 adapted to swing vertically about its fulcrum, of an adhesive finger carried by said rod, a spring normally pressing said finger down on the paper, means for adjusting the tension of said spring, a spiral gear for rotating said

rod, having its teeth so disposed as to press 65 said finger down on the paper in conjunction with said spring with increasing pressure as the said finger encounters resistance to rotation, and means for rotating said spiral gear intermittently in the same direction, substantially 70 as described.

19. The combination with a fulcrumed rod adapted to swing vertically about its fulcrum, 75 of an adhesive finger carried by said rod, a spring normally pressing said finger down on the paper, means for adjusting the tension of said spring, spiral gearing adapted to rotate said rod and having the engaging threads so disposed as at the same time to press said fingers more firmly on the paper when the 80 adhesive finger encounters resistance in rotation, and means for operating said worm-gearing, comprising a drum, a ratchet-and-pawl arrangement, connecting said drum to said worm-gearing, cords rove over said drum, and 85 means for hauling on said cords in reverse directions, substantially as described.

20. In a sheet-lifter, the combination with a casing, of a rod fulcrumed in said casing and carrying at one end an adhesive finger, a 90 sleeve loosely mounted on said rod, a spring engaging said sleeve, and pressing said finger down on the paper, means for holding said rod against lateral vibration, a spiral pinion on said rod, a spiral gear engaging said pinion, said pinion and gear having their teeth 95 so disposed as to press said finger down on said paper in conjunction with said spring when said finger encounters resistance to rotation, and means for rotating said gear, comprising a drum, a ratchet-and-pawl arrangement, connecting said drum to said worm-gearing, cords rove over said drum, and means 100 for hauling on said cords in reverse directions, substantially as described. 105

21. In a sheet-lifter, the combination with a casing, of a rod fulcrumed in said casing and carrying one end of an adhesive finger, a sleeve loosely mounted on said rod, and provided with an annular collar, a spring engaging 110 said annular collar, and pressing said finger down on the paper, means for holding said rod against lateral vibration, a spiral pinion on said rod, a spiral gear engaging said worm, said pinion and gear having their teeth so disposed as to press said finger down on said paper in conjunction with said spring when said finger encounters resistance to rotation, and means for rotating said gear, comprising a 115 drum, a ratchet-and-pawl arrangement, connecting said drum to said worm-gearing, cords rove over said drum, and means for hauling on said cords in reverse directions, substantially as described. 120

22. The combination with a fulcrumed rod 125 adapted to swing vertically about its fulcrum, of an adhesive finger carried by said rod, a spring normally pressing said finger down on

the paper, and spiral gearing adapted to rotate said rod at the same time to press said finger more firmly on the paper when the adhesive finger encounters resistance in rotation, 5 a counter, a treadle, and mechanism operated by said treadle for driving said spiral gearing, and simultaneously operating said counter, substantially as described.

23. The combination with a fulcrumed rod 10 adapted to swing about its fulcrum, of an adhesive finger carried by said rod, a spring normally pressing said finger down on the paper, and means for rotating said rod, substantially as described.

24. The combination with a fulcrumed rod 15 adapted to swing about its fulcrum, of an adhesive finger carried by said rod, a spring normally pressing said finger down on the paper,

and spiral gearing for rotating said rod, substantially as described. 20

25. The combination with a fulcrumed rod adapted to swing about its fulcrum, of an adhesive finger carried by said rod, a spring normally pressing said finger down on the paper, and spiral gearing adapted to rotate said rod 25 and at the same time to press said fingers more firmly on the paper when the adhesive finger encounters resistance in rotation, substantially as described.

In testimony whereof I affix my signature in 30 presence of two witnesses.
